J. Ames.
Sizing Paper.

Patented Sept. 1, 1832.

Fig. 3.

This 1st day of September 1832 Springfield Massachusetts
Letters Patent

The subscriber to whom these Letters Patent and marking shall affect the same
containing a description in the words of the said John Ames himself
of his improvement in the method of sizing paper by machinery.

To all persons to whom these presents shall come, of the town
of Springfield in the County of Hampden and Commonwealth
of Massachusetts, Gentlemen Deans, Clerks

Be it known that the said John Ames, has invented
constructed made and applied to use, a new and improvement in the
method and process of sizing paper by machinery as is hereinafter
set forth and specified viz. Upon a frame of proper strength and
materials I place near and parallel to each other three cylinders of
wood or metal of about 18 or 20 inches in diameter and in length
conforming to the width of the paper to be sized to receive in
a horizontal position upon their respective rows.

The base or bearings upon which the rows of one of said
cylinders rest are fixed on those of the other two are movable
and governed by stops so as to regulate the distance of the cylinders from
each other. Above the line between the middle cylinder and one of
the outer ones and parallel to them I suspend a paper trough
with small holes, in such a position that this sizing matter with which
said trough or paper is to be filled may drop between said two cylinders.
Between said cylinders there are three parallel rollers corresponding in length
with said cylinders and arranged so that the middle roller shall be
rotated a little above the line of the other two. Above the middle roller
I suspend another paper trough as above described to be also filled
with sizing matter. An cylinder roll of felt is made to pass over one
of the outer cylinders & between it & the middle one, then down under
the middle roller then up between the middle cylinder and the other
outer one, then over the latter and down under the last named cylinder
and then up to the place of beginning. The cylinders are to be brought

in close contact by means of the screws applied to the said moveable boxes, or bearings. The paper to be sized, is brought over the outer cylinder, and interposed between it and the middle one, immediately under the sizing trough or pipe, from which the sizing matter drops, and sufficiently wide apart, so that it then passes under the middle cylinder to which it adheres, the gelat paper, down under the middle roller and is wet by the sizing matter exuding from the lower sizing trough or pipe, and again ascending it passes between the other outer cylinder and the middle one, pressing the paper against the latter, and thus sufficiently sizing the other side of the paper. The sized paper is to be then disengaged from the middle cylinder, to which it adheres as aforesaid, and taken off by a cylindrical or other suitable seal.

The moving power is applied to the middle cylinder which communicates motion by friction to the other parts of the machine connected by the coupling belt. The same result may be produced by a different position and arrangement of parts.

I do not claim the cylinder, coupling belt, web or other parts of the machine separately as, my invention, all that I claim specifically as mine is, the several parts of said machine in combination with the use of coupling belt web for the purpose of sizing paper.

In testimony that the foregoing is a true specification of my said improvement, as above described, I have hereunto set my hand the twenty second day of August anno Domini One thousand Eight hundred and Thirty two.
